UNITED STATES PATENT OFFICE.

LOUIS STEINBERGER, OF NEW YORK, N. Y. ASSIGNOR TO GEORGE KUEHL,
OF CHICAGO, ILLINOIS.

DESIGN FOR A GAME-COUNTER.

SPECIFICATION forming part of Design No. 20,710, dated May 5, 1891.

Application filed February 24, 1891. Serial No. 382,631. Term of patent 14 years.

To all whom it may concern:

Be it known that I, LOUIS STEINBERGER, a citizen of the United States of America, residing at New York, in the county and State 5 of New York, have invented a certain new and useful Design for Game-Counters, of which the following is a specification, reference being had therein to the accompanying drawings.

10 The design consists in the novel ornamentation for a game-counter as hereinafter set forth, and shown in the drawings.

In said drawings, Figure 1 illustrates a face view of a game-counter ornamented with my 15 design, and Fig. 2 is a cross-section of the same.

Referring to said drawings, the outer circular line indicates the marginal edge of a game-counter. The said game-counter is ornamented by placing thereon the representation 20 of a clover-leaf and a horseshoe. The representation of the clover-leaf is in the background and the representation of the

horseshoe is in the foreground and in front of said representation of the clover-leaf, and 25 both of said figures are approximately arranged centrally upon the face of the game-counter. Around the said ornamentation and concentric with and arranged a slight distance from the periphery of the game-counter 30 a circle is shown, which serves to add a pleasing effect to the same. It will be understood, of course, that the design shown and described is placed upon both faces of the game-counter and serves to ornament the same in an effective, symmetrical, and harmonious manner, 35 which is agreeable and pleasing to the eye.

I claim as my invention—

The design for a game-counter, substantially as shown and described. 40

In testimony whereof I affix my signature in presence of two witnesses.

LOUIS STEINBERGER.
